UNITED STATES PATENT OFFICE.

ANTON WAIZ, OF WORCESTER, MASSACHUSETTS, ASSIGNOR OF ONE-HALF TO ELIJAH L. GREENSLIT, OF WORCESTER, MASSACHUSETTS.

TAP EXTENSION.

1,088,855.

Specification of Letters Patent. Patented Mar. 3, 1914.

Application filed April 2, 1913. Serial No. 758,350.

To all whom it may concern:

Be it known that I, ANTON WAIZ, a citizen of the United States, residing at Worcester, in the county of Worcester and Worcester, State of Massachusetts, have invented a new and useful Tap Extension, of which the following is a specification.

This invention relates to a pulley tap or more specifically, to a device for holding an ordinary tap to make it serve the purpose of an ordinary pulley tap. As is well known pulley taps as usually made are the same as ordinary short taps, except that they have a long shank integral with the cutting end of the tap. This renders it necessary to have in stock taps of various sizes made with the long shank.

The principal object of this invention is to provide a construction by which ordinary short taps can be used as pulley taps by combining with them a detachable holder or shank. This is especially constructed for the purpose of connecting it with the short taps, receiving the operating wrench, and holding and guiding the tap during its operation; also to provide a construction of this kind in which a plurality of taps of different lengths can be used with a single holder, thus, reducing the expense.

Reference is to be had to the accompanying drawings, in which—

Figure 1 is a central sectional view of a pulley showing how a pulley tap is used thereon when constructed in accordance with this invention, and Fig. 2 is an elevation of a tap extension partly in section on a central longitudinal plane.

The invention is shown in a simple form involving a main shank *a* of cylindrical form and uniform diameter throughout, except at the end where it has a non-circular projection *b*, in the present instance, square. At the other end it has a cylindrical socket *c* of a diameter sufficient to receive the cylindrical end of a tap *A*. At the end of this socket is a non-circular socket *d* of the same shape and size substantially as the projection *b* and in axial alinement therewith. It may, however, be of slightly different length.

In operation an ordinary tap *A* having a projection *B* adapted to fit the socket *d* and having a cylindrical portion *C* adapted to fit the socket *c* is introduced into these socket

ets so that the cutting end thereof projects 55 therefrom. It will be understood that when this tap is used for ordinary purposes the square projection *B* is designed for the application of a wrench thereto, but when it is applied to this attachment the same 60 wrench *E* can be applied to the projection *b*. The tap being applied to the attachment as indicated, the whole device is introduced into the pulley *F*, through the holes *G* in the same manner as an ordinary pulley tap 65 and operated by a wrench from the end of projection *b* in the ordinary way. My device contains several features vital to such a construction, namely, it corresponds in outside diameter to the outside diameter of 70 the tap, the hole in the rim of a pulley through which said tap is to be passed always being of the same diameter as the tap used on said pulley; and, furthermore, the extension being of the same diameter 75 on the tap, the extension always has a bearing in the hole of the rim of the pulley. This prevents springing or wobbling and thereby reduces the liability of breakage, because it is always in perfect alinement. 80

It will be obvious that a number of different length taps *A* can be employed at different times with this attachment and that the same wrench is employed with the attachment as would be employed if the tap 85 were used alone. It will be seen moreover, that the tap is not only centered and positively driven by having its non-circular portion *D* inserted in the socket *d*, but it is guided and held accurately in central 90 position by having its cylindrical portion below held in the large circular socket *c*. In addition to this it will be seen that the holding device *a* is of substantially uniform diameter throughout and only a little larger 95 than the shank of the tap so that it will pass through the holes *G* in the pulley designed for receiving the shank of the ordinary tap wrench.

Although I have illustrated and described 100 a single embodiment of the invention, I am aware of the fact that modifications can be made therein by any person skilled in the art without departing from the scope of the invention as expressed in the claims. Therefore I do not wish to be limited to all the 105 details of construction herein shown and described, but

What I do claim is:—

1. As an article of manufacture, an extension for a machinist's hand tap to enable it to be used as a pulley tap consisting of a substantially cylindrical rod having a non-circular projection at one end for receiving a wrench and a socket at the other end of substantially the same size and shape as said projection and constituting the sole means for receiving the end of a tap having substantially the same external diameter as that of the extension.
2. As an article of manufacture, a tap extension consisting of a substantially cylindrical rod having a non-circular projection at one end for receiving a wrench and a socket at the other end of substantially the same size and shape as said projection for receiving the end of a tap, and having a cylindrical socket constituting an integral part of the last named end beyond the non-

circular socket for receiving and rigidly holding the cylindrical part of the tap.

3. The combination with a tap of a tap extension consisting of a substantially cylindrical rod in a single piece having substantially the same outside diameter as the threads of said tap and having a non-circular projection at one end and a socket at the other end of substantially the same size and shape as said projection and in axial alignment therewith, said socket constituting the sole means for receiving and holding the end of the tap.

In testimony whereof I have hereunto set my hand, in the presence of two subscribing witnesses.

ANTON WAIZ.
